UNITED STATES PATENT OFFICE

146,867

DESIGN FOR A LAMP OR SIMILAR ARTICLE

Arthur G. Miller, Long Beach, Calif., assignor of one-third to Delbert D. Grant and one-third to Johnnie W. Miller, both of Long Beach, Calif.

Application November 7, 1945, Serial No. 123,532

Term of patent 3½ years

(Cl. D48—20)

To all whom it may concern:

Be it known that I, Arthur G. Miller, a citizen of the United States residing at Long Beach, in the county of Los Angeles and State of California, have invented a new, original, and ornamental Design for a Lamp or Similar Article, of which the following is a specification, reference being had to the accompanying drawing, forming a part thereof, and in which:

Fig. 1 is a side elevational view of a lamp or similar article showing my new design; and

Fig. 2 is a reduced scale cross-section on line
2—2 of Fig. 1.

The dominant features of my design reside in the portions shown in full lines.

I claim:

The ornamental design for a lamp or similar article, as shown and described.

ARTHUR G. MILLER.
